[57] **CLAIM**

The ornamental design for an electronic article surveillance interrogation panel unit, as shown and described.

DESCRIPTION

FIG. 1 is a perspective view of an electronic article surveillance interrogation panel unit showing our new design, wherein the opposite sides of the two panels are the same in appearance as that shown in the right panel; FIG. 2 is a front elevational view thereof, with the rear being a mirror image;

FIG. 3 is a top plan view thereof;

FIG. 4 is a perspective view of a second embodiment thereof, wherein opposite side is the same in appearance as the side of the panel shown on the right in FIG. 1; and,

FIG. 5 is a perspective view of a third embodiment thereof, wherein the opposite sides of the three panels are the same in appearance as that shown in the middle and right panels.

FIG. 1

FIG. 2

FIG. 3

FIG. 4

FIG. 5
